UNITED STATES PATENT OFFICE.

JAMES MACPHAIL, OF DAVENPORT, IOWA, ASSIGNOR, BY MESNE ASSIGNMENTS, TO DEERE & COMPANY, OF MOLINE, ILLINOIS, A CORPORATION OF ILLINOIS.

TOOTH-HOLDER FOR SULKY HAY-RAKES.

1,126,813.

Specification of Letters Patent.

Patented Feb. 2, 1915.

Application filed July 9, 1913. Serial No. 778,018.

To all whom it may concern:

Be it known that I, JAMES MACPHAIL, a citizen of the United States, residing at Davenport, in the county of Scott and State of Iowa, have invented certain new and useful Improvements in Tooth-Holders for Sulky Hay-Rakes, of which the following is a specification, reference being had to the accompanying drawings.

10 This invention relates to means for holding in place on a rake-head the heavy wire teeth of the rake.

The object of the invention is to provide a holder that can be formed readily and cheaply from a single sheet of metal; that will be very strong and durable and that, while holding the teeth very securely, will permit the "laterals" or turned upper ends of the teeth to slightly rock as required 20 when the teeth are forced to give or oscillate on account of meeting obstructions. I accomplish these objects by the construction of holder shown and hereinafter particularly described. That which I believe to be 25 new will be set forth in the claims.

In the drawings,—Figure 1 is an elevation of my improved tooth-holder secured in position to a rake-head and showing also the upper parts of several rake-teeth secured in 30 place by said holder; Fig. 2 is an enlarged vertical section through the devices of Fig. 1; and Fig. 3 is an enlarged perspective view of the holder, looking toward the inner face thereof.

35 In the several figures of the drawing in which corresponding parts are indicated by the same reference letters: A and A' indicate the two walls, respectively, of an angle-iron rake-head.

40 B indicates my improved tooth-holder which is formed from a single piece of metal made in the shape of a channel, the back wall of which is indicated by b and the upper and lower flanges thereof by c and d, respectively, the said lower flange d being substantially at right angles to the back wall b while the upper flange c is turned sharply downward so as to bring its free edge nearly opposite the longitudinal center of the back wall b, for a purpose hereinafter explained.

e indicates a number of notches in the inclined flange c and in alinement therewith are notches f in the other flange d, such 55 notches e and f being provided to receive

the rake-teeth. For convenience in connecting and disconnecting the rake-teeth several of the holders are employed placed end to end across the rake and each holder, as stated, is adapted to secure in place a number of the teeth, and as such number of teeth varies according to circumstances or the ideas of the user, each holder will preferably be provided with more sets of notches e and f than are in use for teeth at any one time. By so providing extra notches the user can, by a proper selection of notches, space the teeth as desired.

D indicates the rake-teeth that are secured in place by the holder, such teeth being formed, as usual, of heavy spring wire, and each having the ordinary turned part at its upper end, which turned part—generally known in the trade as a tooth "lateral"—is indicated in the drawing by D'. As stated, a number of the holders B will be employed on a single rake in order to secure all of the rake-teeth in place, such holders being arranged end to end along the angle-iron head. The edges of the two flanges c and d bear against the inner face of the wall A of such head, and the upper part of the wall b of the holder where it bends to form the flange c bears against the wall A' of the head.

E indicates securing bolts for attaching the holder to the wall A, the nuts on the bolt being indicated by g. When the holder is secured in place by these bolts and nuts the several teeth held thereby will extend 90 through the notches e and f in the flanges c and d, respectively, and the tooth "laterals" will be inclosed or housed in the triangular chamber formed by the downwardly inclined flange c of the holder and the walls A, A' of the angle-iron head. Fitting in such housing or inclosure the "laterals" are held against rattling or wabbling but are free to have a slight turning or hinge-like movement when the teeth are 100 sprung by meeting an obstruction.

With the parts in position it will be seen that the edge of the inclined flange bears not only against the wall A of the angle-iron head but also against the securing bolts 105 E. Such a construction insures great strength and very effectively resists any tendency to crush or distort the holder due to excessively tight screwing of the nuts on the bolts, for, as will be appreciated, such 110

inclined flange bearing against the bolts acts as a stiffening brace for the holder as a whole. Furthermore, it will be evident that increasing the tension of the bolt transfers the pressure at a right angle to the draw of the bolt and causes the upper edge of the tooth-holder to bear tightly against the angle-iron. The holder thus being brought firmly in contact with both walls of the angle-iron is held so securely that no shifting action can take place, notwithstanding the very considerable strains brought against it by the tooth laterals during the operation of the rake.

15 That which I claim as my invention, and desire to secure by Letters Patent is,—

1. The combination with an angle-iron rake-head, of a tooth-holder comprising a channel-bar having a notch in each of its flanges to receive a tooth, said flanges having their edges bearing against the angle-iron, and means for securing said channel-bar against one wall of the angle-iron, one of the flanges of the channel-bar being inclined toward said securing means.

2. The combination with an angle-iron rake-head, of a tooth-holder comprising a channel-bar having a notch in each of its flanges to receive a tooth, said flanges having their edges bearing against the angle-iron, and means for securing said channel-bar against one wall of the angle-iron, one of the flanges of the channel-bar being inclined toward and bearing against said securing means.

3. The combination with an angle-iron rake-head, of a tooth-holder comprising a channel-bar having a notch in each of its flanges to receive a tooth, said channel-bar having the edges of its flanges directed toward the inner face of one wall of the angle-iron, one of said flanges being inclined whereby it forms in connection with the walls of the angle-iron a triangular housing adapted to receive a tooth lateral, and means for securing the holder to the angle-iron.

4. The combination with an angle-iron rake-head, of a tooth-holder comprising a channel-bar having a notch in each of its flanges to receive a tooth, said channel-iron bearing against the inner face of one wall of the angle-iron and having the edges of its flanges bearing against the inner face of the other wall of the angle-iron, one of the said flanges being inclined, whereby a triangular housing is formed by said inclined flange and the walls of the channel-iron adapted to receive a tooth lateral, and means for securing the said holder to the angle-iron.

5. The combination with a rake-head of a tooth-holder comprising a channel-bar having tooth-receiving openings in its flanges, said flanges being directed toward the rake-

head, and means for securing said holder to the rake-head, one of the flanges of the channel-bar being inclined toward the said securing means to form a support for a rake-tooth lateral placed in the angle of the 70 rake-head.

6. The combination with a rake-head of a tooth-holder comprising a channel-bar having tooth-receiving openings in its flanges, said flanges being directed toward the rake-head, and means for securing said holder to the rake-head, one of the flanges of the channel-bar being inclined toward and bearing against both the securing means and the 75 rake-head.

7. The combination with an angle-iron rake-head, of a tooth-holder comprising a bar having a downwardly-turned flange at its upper edge notched to receive a tooth, and means for securing said holder against 80 one wall of the angle-iron rake-head and below the other wall thereof, whereby a housing is formed for a tooth lateral by said two walls of the rake-head and the downwardly-turned flange of the holder.

8. The combination with an angle-iron rake-head, of a tooth-holder comprising a bar having an inclined longitudinal flange, said holder having two aligned notches to receive a tooth, one of such notches being 85 formed in said flange, means for securing said holder against one wall of the angle-iron rake-head and below the other wall thereof, whereby a housing is formed for a tooth-lateral by said two walls of the rake- 90 head and the said inclined flange.

9. As a new article of manufacture, a rake-tooth holder formed of a channel-bar, one flange thereof being inclined at an acute angle.

10. As a new article of manufacture, a rake-tooth holder formed of a channel-bar, one flange thereof being inclined at an acute angle, and the wall of the channel-bar having a bolt opening located with reference to 105 such inclined flange that a bolt passed through the opening will lie immediately below the edge of such flange.

11. As a new article of manufacture, a rake-tooth holder formed of a bar bent upon 115 itself to form an inclined longitudinal flange, the edge of which lies opposite the inner face of the bar and in which flange is a notch for the passage of a rake-tooth, said bar being provided with a bolt opening 120 therethrough located with reference to such flange that a bolt passed through the opening will form an abutment for the edge of such flange.

12. As a new article of manufacture, a 125 rake-tooth holder formed of a bar bent upon itself to form an inclined longitudinal flange, the edge of which lies opposite the inner face of said bar and in which flange is a notch for the passage of a rake-tooth.

13. As a new article of manufacture, a rake-tooth holder formed of a bar bent upon itself to form an inclined longitudinal flange the edge of which lies opposite the inner face of the bar, said holder being provided with two alined notches for receiving a rake-tooth, one of said notches being in said inclined flange.

14. The combination with an angle-iron 10 rake-head, of a tooth-holder comprising a bar having an inclined longitudinal flange at its upper edge notched to receive a tooth, and means for forcing said holder tightly against both walls of the angle-iron, said inclined flange and the walls of the angle-iron forming a housing for a tooth lateral.

15. The combination with an angle-iron 20 rake-head, of a tooth-holder comprising a bar having an inclined longitudinal flange at its upper edge notched to receive a tooth, said inclined flange and the walls of the angle-iron rake-head forming a housing for the reception of a tooth lateral, and a bolt for securing said holder to one wall of the 25 rake-head, the edge of said flange bearing against said bolt and that wall of the angle-iron through which such bolt passes, whereby the tightening of the bolt will draw the holder toward such wall and also cause it 30 to press tightly against the other wall of the angle-iron.

16. The combination with an angle-iron 35 rake-head, of a tooth-holder comprising a bar bent adjacent to and parallel with one of its longitudinal margins to form a wall of a housing adapted to receive rake teeth laterals, the walls of said angle-iron constituting a portion of said housing, said tooth-holder having a series of pairs of alined 40 notches to receive the body portions of rake-teeth, and said tooth-holder having three lines of contact with the inner faces of the angle-iron, and means for securing the holder to said angle-iron.

17. The combination with an angle-iron 45 rake-head, of a tooth-holder comprising a bar bent adjacent to and parallel with one of its longitudinal margins to form a wall of a housing adapted to receive rake teeth laterals, the walls of said angle-iron constituting a portion of said housing, said tooth-holder having a series of pairs of alined notches to receive the body portions of rake-teeth, and said tooth-holder bearing at its 50 edges against the inner face of one wall of the angle-iron and also bearing, along a line between such edges, against the inner face of the other wall of the angle-iron, and means for securing the holder to said angle-iron.

18. The combination with an angle-iron 60 rake-head, of a tooth-holder comprising a bar bent adjacent to and parallel with one of its longitudinal margins to form a wall of a housing adapted to receive rake teeth laterals, the walls of said angle-iron constituting a portion of said housing, said tooth-holder having a series of pairs of alined notches to receive the body portions of rake-teeth, and having a turned portion directed 65 toward that wall of the angle-iron to which the holder is secured, and means for securing the holder to said angle-iron.

19. The combination with an angle-iron 70 rake-head, of a tooth-holder comprising a bar bent to form a member having its edge 75 directed toward one wall of the angle-iron and adapted to support a tooth lateral between such member and the walls of the angle-iron, said holder having two alined and separated notches for receiving the 80 main or body portion of a rake-tooth, and means for securing the holder to the angle iron.
